UNITED STATES PATENT OFFICE.

GURDEN L. CHAMBERLIN, OF MARIETTA, OHIO.

CAR-COUPING.

SPECIFICATION forming part of Letters Patent No. 274,106, dated March 20, 1883.

Application filed June 24, 1882. (No model.)

To all whom it may concern:

Be it known that I, GURDEN L. CHAMBERLIN, a citizen of the United States, and a resident of Marietta, in the county of Washington and State of Ohio, have invented a new and valuable Improvement in Car-Couplers; and I do hereby declare that the following is a full, clear, and exact description of the construction and operation of the same, reference being had to the annexed drawings, making a part of this specification, and to the letters and figures of reference marked thereon.

Figure 1 of the drawings is a bottom view of my coupler. Fig. 2 is a side view of the same. Fig. 3 is a front view, and Fig. 4 is a detail view of lever K.

This invention has relation to car-coupling devices; and it consists in the construction and novel arrangement of parts, as will be hereinafter fully described, and pointed out in the claims appended.

In the accompanying drawings, the letters A A designate the coupling devices, which are duplicates of each other in all essential particulars. In each of these coupling devices B represents a bed-plate secured to the under side of the draw-bar or draw-head C by means of bolts, clamps, or other sufficient fastening devices. The draw-heads may be those which are now in common use for the ordinary link-and-pin connection, as the coupling devices herein described are so arranged as not to interfere with the employment of the link-and-pin coupling, so that a car which is only provided with the latter form of coupling can be readily connected to a car having the automatic coupling.

D represents a bridge-plate, which is bolted to the bed-plate B. Pivoted to the rear portion of this bridge-plate and somewhat at one side thereof are the long lever-jaws E E, which are formed with beveled hook-shaped ends a, and are extended in rear of their pivots, as indicated at b. Between the ends of the extensions b is arranged a spring, c, which is designed to have an expanding tension, so that it will act to press the extensions or arms b of the levers apart, and thereby close the hooked ends or jaws a. Between the levers E is arranged an elongated cam, d, the stem of which is journaled in a bearing in the bridge-tree. The cam is provided with a transverse lever,

F, the arms of which project laterally on each side of the coupling devices and serve as handles, whereby the lever can be actuated to turn the cam d, and thereby press the coupling-jaws a apart. The stem of the cam d is provided with a square arbor in order that it may be rigidly secured to the lever F.

G represents a pivoted upright, the foot of which is connected to an arm of the lever F by means of a link, e. The upright stem G may be arranged in convenient position to extend upward through the platform or floor of the car, and should be provided at its upper end with an arm or handle, f, whereby it may be turned to move the lever F and its cam d. This uncoupling device can therefore be operated from the top as well as from either side of the car.

H indicates a lever-arm extending parallel to the lever-jaws, being pivoted also to the bridge-plate at the side of said jaws, as shown in the drawings. This lever is provided with a loop, g, at its front end, said loop being rectangular in form, and having its front bar, h, rounded, so that it will pass easily between the beveled hook-heads of the coupling-jaws of an approaching car. The loop is arranged vertically, and is of sufficient vertical span to provide for an easy coupling between cars of different heights. The loop arm or lever H extends back of its pivotal point, as indicated at i, and this rear arm or extension is connected to the bridge-plate or a bearing thereon by a vertical spring, j, the object of this spring-connection being to allow the loop-arm to play or yield when coupled and to hold it in line with the jaws of an approaching car when about to be coupled therewith. The coupling devices are thus arranged to accommodate themselves to the motion of the cars.

I designates a slide, which moves back and forth on a bearing, k, of the bridge-plate, and is connected to the lever F by a pivot-pin. This slide is formed with notches or depressions n, and is designed to engage the outer end of a spring-arm, l, which carries the lateral stops m, consisting of two pins which extend through openings a' in the bridge-plate. The spring-arm l is designed to be held up by the slide I when the cars are coupled, and in this position the lateral stops are retracted, so that the loop-arm, on each side of which they are ar-

ranged, is free to play; but when the transverse lever is moved to operate the cam in uncoupling one of the notches or depressions *n* is brought under the spring-arm, allowing it to move downward, so that its stops *m* are projected through the bridge-plate on each side of the loop-arm and serve to hold it steady, thereby preventing the loop from hanging to either of the hook-heads of the coupling-jaws.

10 In order to hold the jaws open a sufficient time to effect a complete disengagement of the loop, a spring-catch, *K*, is provided. This is pivoted to an arm, *p*, of the bed-plate and extends forward under the transverse lever *F*, which it engages by means of the catch-lug *q* on its upper edge when said lever is moved sufficiently to open the jaws.

15 *L L'* designate the bumper-rods, which extend from front to rear over the coupling-jaws and coupling-loop, and slide in bearings *r*, which are connected to the bed-plate, usually, as shown in the drawings. The front ends of these slide-rods project a little farther forward than the coupling jaws and loop, and are provided with disk-heads *s* of sufficient diameter to insure engagement with the slide-rods of an approaching car. These rods are also provided with springs *t*, which are respectively arranged between a slide-bearing, *r*, and a collar-bearing, *b'*, of each rod, and serve to provide for an elastic reaction, replacing the rod in its forward position when relieved from the pressure holding it back. The rod *L* is also provided with a globular enlargement or ball-collar, *v*, which, when said rod is pressed backward, is designed to engage a lug or swell, *z*, on the

spring-catch *K*, depressing said catch and disengaging it from the transverse lever *F*. These devices are always ready for action and are automatic in the coupling operation. If the coupling-jaws should be set open by the action of the spring-catch, a disengagement thereof will be at once effected when the bumper-rods are pushed back as the cars come together.

Having described this invention, what I claim, and desire to secure by Letters Patent, is—

1. In an automatic car-coupling, the transverse cam-lever *F*, spring-catch *K*, and sliding bumper-rod *L*, having a replacing-spring, *t*, and an enlargement, *v*, to depress the spring-catch, substantially as specified.

2. In an automatic car-coupling, the combination, with the loop-arm *H* and the lateral stop-spring *l*, of the bridge-plate having the perforations *a'* and the slide-bearing *k*, the check-slide *I*, and the transverse cam-lever *F*, substantially as specified.

3. In an automatic car-coupling, the combination, with the lever-jaws *E* and the loop-arm *H*, of the bumper-rods *L L'* and springs *t*, the opening-cam *d* and cam-lever *F*, the spring-closer *e*, the spring-catch *K*, and the depressing or disengaging device for said spring-catch, substantially as specified.

In testimony that I claim the above I have hereunto subscribed my name in the presence of two witnesses.

GURDEN L. CHAMBERLIN.
